UNITED STATES PATENT OFFICE.

JAMES P. FISHER, OF BARTLESVILLE, OKLAHOMA.

STEAM-GENERATOR.

1,273,596.

Specification of Letters Patent. Patented July 23, 1918.

Application filed June 24, 1916. Serial No. 105,589.

To all whom it may concern:

Be it known that I, JAMES P. FISHER, a citizen of the United States, residing at Bartlesville, in the county of Washington and State of Oklahoma, have invented certain new and useful Improvements in Steam-Generators, of which the following is a specification, reference being had thereto to the accompanying drawing.

10 The invention relates particularly to steam generators using gaseous fuel and acting upon the water while the latter is passing through a relatively small passage-way, no large reservoir of heated water being present. It will be understood, however, that the invention in all of its aspects is not necessarily limited to a boiler or generator of this type.

One of the objects of the invention is to 20 provide an improved arrangement of the water containing chambers whereby the maximum amount of heat is absorbed from the fuel and whereby the heating surfaces are protected against burning. Another 25 object of the invention is to provide means whereby a high velocity of water and steam may be maintained, thus preventing the formation and the deposit of scale. Another object of the invention is to provide 30 an improved means for separating the water and steam at a point prior to the entrance of the water into the main vaporizing chamber. A further object is to provide an improved construction for the feeding, 35 mixing and burning of the gaseous fuel whereby a uniform combustible mixture is secured and whereby the heat is distributed and conducted to the heating surfaces. Still another object of the invention 40 is to provide an improved regulating mechanism whereby the amount of fuel supplied is controlled and regulated by the steam pressure. Other objects of the invention 45 are to provide certain improved arrangement of parts whereby there is obtained a very simple and compact structure which is capable of being taken apart for inspection and repair. Still other objects of the invention will be apparent from the following 50 specification and claims.

In the accompanying drawings I have shown two embodiments of the invention, it now being my preference to embody the invention in one of these two ways. But it will be understood that the invention can be embodied in other ways and that the drawings are to be understood as serving illus-

trative purposes only and not as defining or limiting the scope of the invention, the appended claims being relied upon for that purpose.

Of the drawings,

Figure 1 is a vertical sectional view showing one embodiment of the invention, certain of the parts being shown in elevation for the sake of clearness and simplicity.

Fig. 2 is a sectional view taken along the line 2-2 of Fig. 1.

Fig. 3 is a sectional view taken along the line 3-3 of Fig. 1.

Fig. 4 is a vertical sectional view showing another embodiment of the invention.

A steam generator embodying my invention comprises a heating or combustion chamber having heat conducting metallic walls with which the water to be vaporized is brought into contact. The arrangement is such that the cold water first contacts with that part of the heating surface which is engaged by the gases of combustion as 80 they are about to enter the exhaust. In this way the maximum amount of heat is absorbed from the gases causing them to be reduced to the minimum temperature before being discharged. The water next passes to 85 that part of the heating surface which is engaged by the gases during combustion. At this point the temperature of the gases is greatest and without proper protection there is a tendency for the walls of the 90 combustion chamber to become unduly heated and burned. With my construction, however, this part of the heating surface is engaged by water containing little or no steam with the result that the said surface 95 cannot be brought to a temperature above the boiling point. After this the water at or about boiling temperature is conducted to an intermediate part of the heating surface where the temperature is reduced 100 somewhat below that of the part last above mentioned and here the water is vaporized.

The combustion chamber and the water holding and conducting passages can be constructed in any of a number of ways. I 105 prefer, however, to provide a central metallic tube 1, such as is shown in Fig. 1 of the drawings, a section of boiler tubing having been found to be suitable. This tube is preferably arranged vertically, as shown in Fig. 1, and means are provided for causing a flow of gas therethrough. Preferably, as shown in Fig. 1, there is provided a suction fan 2 which is connected by means of a pipe

3 to one end of the tube 1, the connection being through the lower end as shown in Fig. 1. A major portion of the tube 1 is filled with finely divided granular refractory material as indicated at 4. When the exhaust connection is made at the lower end, means such as indicated at 5 are provided for supporting the said granular material. At the other end of the tube at the top of 10 the granular material, there is provided a plate 6 which has a number of perforations therein. Some of these perforations, as indicated at 7, communicate with the atmosphere at the top of the plate, and another 15 perforation, shown as centrally disposed, communicates with a pipe 8 which leads from a suitable source of gas supply. The gas is preferably maintained at atmospheric pressure by any suitable means, 20 such as a balanced gasometer, this means, however, not being shown as it of itself constitutes no part of my present invention.

It will be understood that when the fan 2 is operated a partial vacuum is created at 25 the end of the tube 1 which is transmitted through the tube to the top, causing air to be drawn in through the apertures, and gas to be drawn in through the pipe 8. The air and gas move through the interstices of the 30 granular material and quickly become mixed. Combustion is started in the upper part of the tube and the air and gas unite causing intense heat. The zone of combustion begins a short distance below the plate 6 at the 35 plane at which the mixture of gas and air is sufficiently complete to be combustible. The granular material not only causes the mixing of the gas and air, but also serves to retard the flow of the mixture holding it in 40 the upper part of the pipe until combustion is complete; and the flow of the gases of combustion down through the pipe is also retarded giving ample opportunity for the heat to be absorbed by the walls of the tube.

45 The refractory material, by causing the intimate commingling of the air and gas as before stated, insures great rapidity of combustion and a high rate of transmission of heat to and through the tube walls.

50 Surrounding the combustion or heating chamber, in this case the tube 1 is a water chamber or container preferably divided into three separate sections. The upper section 9 of the water container is formed by 55 a tube 10 arranged concentrically with the tube 1; the central section 11 of the water container is formed by a tube 12 also concentric with the tube 1; and the lower section 13 of the water container is formed by 60 a tube 14 also concentric with the tube 1. The three sections of the water container are separated from each other. For separating the sections 9 and 11 there is preferably provided a metal plate 15 which has 65 water tight contact with the tube 1 and

which is clamped between the two flanges 16 and 17 secured respectively to the tubes 10 and 12. Between the container sections 11 and 13 there are preferably provided two plates 18 and 19 between which is clamped 70 a copper gasket 20 which engages the pipe 1. The two plates 18 and 19 are engaged by flanges 21 and 22 secured respectively to the tubes 12 and 14. The upper end of the tube 10 is contracted and is provided with a 75 stuffing box 23 which engages the tube 1 providing a joint which is tight but which nevertheless permits relative movement between the tubes 1 and 10 on account of differences in expansion and contraction. The lower end of the tube 14 is similarly contracted and is provided with a similar stuffing box 24 which engages the tube 1.

In the chamber 13 there is provided a spiral baffle or vane 25 which connects with the outer surface of the tube 1 and the inner surface of the tube 14. Interposed between adjacent parts of this vane are separators 26 arranged at suitable intervals. In the upper chamber 9 is a similar spiral vane 27 85 having similar separators 28, this vane differing from the vane 25 in that the pitch is somewhat greater. In the middle chamber 11 is another spiral vane 29 with separators 30. The pitch of this vane is considerably 90 greater than that of the vane 27.

At 31 is a water supply pipe leading into the bottom of the chamber 13. The water entering through this pipe flows around the spiral passage between the parts of the vane 25 and finally reaches the upper end of the chamber 13. In passing through this spiral passage the water is brought into intimate contact with the part of tube 1 which contains the gases about to be exhausted. The 100 separators 26 in addition to holding the parts of the vane properly spaced also serve to agitate the water and insure all parts of it being brought into contact with the heating surface. The water being cold absorbs 105 the maximum amount of heat from the gases, leaving them relatively cool as they pass into the tube 1. It will be observed that in this section of the tubes the counter-flow principle is used thus securing the maximum cooling effect on the gases. 110

From the upper end of the chamber 13 the water passes through a pipe 32 to the upper end of the chamber 9. Here the water enters the spiral passage between the parts 115 of the vane 27 and flows to the lower end of the chamber 9; the separators 28 serving to insure contact of all of the water with the heating surface. In passing through this spiral passage the water contacts with that 120 part of the tube 1 which incloses the burning gases. The water entering this chamber 9, while somewhat heated, is nevertheless somewhat below the boiling point, the result being that only a small part of the water is 125 130

vaporized. There is therefore assurance that in this chamber the walls of the tube 1 will be in contact with water and thus protected against burning which might otherwise result because of the intense heat on the interior of the tube. From the bottom of the chamber 9 the water, together with whatever steam may have been formed, passes through the pipe 33 into the reservoir 34. The pipe 33, after entering the reservoir, is turned up at 35 thus bringing its discharge point near the top of the reservoir. In this reservoir any steam that has been formed is separated from the water which collects in the bottom, its height being registered by the gage glass 36. From the bottom of the reservoir 34 the water passes through a pipe 37 into the lower end of the chamber 11. Here the water passes through the spiral passage between the parts of the vane 29 and is vaporized by its contact with the walls of the tube 1, these walls inclosing the hot gases of combustion. The separators 30 assist in the vaporization by insuring the contact of all of the water with the heating surface. All of the water is converted into steam in this chamber 11 and the steam is discharged through the pipe 38. A by-pass pipe 39 connects the upper section of the chamber 11 with the upper part of the reservoir 34 thus serving to maintain a uniform pressure in the chamber and reservoir, and also serving to conduct the steam collected in the reservoir into the chamber where it can be discharged through the pipe 38. The by-pass pipe 39, by equalizing the pressure in the container section 11 and in the reservoir, as before mentioned, serves to maintain the water in the reservoir and in the section 11 at the same level. For this reason the gage glass 36 serves to indicate the level of the water in the vaporizing chamber as well as in the reservoir. It is therefore possible for one to observe the water level and ascertain whether or not the water is being vaporized in the vaporizing chamber at the proper rate. Preferably a baffle is provided in the reservoir at 40 to prevent the discharge of water into the pipe 39. A steam gage 41 is preferably connected with the reservoir 34 to indicate the pressure.

Inasmuch as the gas supply is maintained at atmospheric pressure, it will be clear that the ratio of gas to air will be constant notwithstanding variations in the rate of flow. In practice the rate of flow of gas and air is so controlled with respect to the rate of water supply, that all of the water entering the chamber 11 is completely vaporized. By increasing the amount of gas and air any desired degree of superheat can be given to the steam. Preferably the fan 2 is driven by a turbine or other steam motor receiving its steam from the pipe 38 through a suit-

able supply pipe as indicated at 43. The connections are such that as the steam pressure in the pipe 38 increases above normal, the speed of the turbine and fan is reduced thus reducing the supply of fuel and permitting the steam pressure to drop. When the steam pressure falls below normal, the speed of the turbine and fan is increased thus increasing the amount of fuel and causing steam pressure to rise. 75

It will be observed that the space available for the flow of the water, or the water and steam, increases from the point of inlet at 31 to the point of discharge at 38. In the chamber 13 the spiral passage is relatively narrow as there is only water to be handled; in the chamber 9 the spiral passage is somewhat wider as some steam is present; and in the chamber 11 the spiral passage is very much wider as there is much steam to be accommodated. All of the said spiral passages are designed to give high velocity of flow therethrough so as to prevent the deposit of scale on the heating surface. 85

From the foregoing description and from the drawings it will be clear that the whole mechanism is so constructed as to be capable of being readily taken apart. The outer tubes 10, 12 and 14 can be removed from the tube 1 and can be separated from each other, and the several spiral vanes can be removed. In this way all of the parts of the apparatus are readily available for inspection or repair or replacement. 90

In Fig. 4 there is shown another embodiment of the invention which is very similar to that shown in Fig. 1, the essential difference being that the gases are drawn out of the top of the combustion chamber instead of out of the bottom. In this connection 1^a represents the central combustion tube connected at its top with a fan 2^a by means of a pipe 3^a. Granular material 4^a is placed in the tube and is supported on a plate 6^a similar to the plate 6 already described, and connected with a gas pipe 8^a. Surrounding the tube 1^a are tubes 14^a and 10^a provided respectively with stuffing boxes 24^a and 23^a engaging the tube 1^a. The two tubes 14^a and 10^a are joined by flanges 22^a and 16^a between which are plates separating the upper chamber 13^a from the lower chamber 9^a. Water is admitted to the upper part of the chamber 13^a through the pipe 31^a and flows downward through the spiral passage 110 provided by the spiral vane 25^a. From the lower part of the chamber 13^a the water passes through a pipe 33^a to a reservoir 34^a. From the bottom of the reservoir 34^a the water passes through a pipe 37^a to the bottom of the chamber 9^a. In the bottom of this chamber there is a spiral vane 27^a forming a spiral passage along which the water passes upward. In the upper part of the chamber 9^a is another spiral vane 29^a form- 115 120 125 130

ing a spiral passage through which the water, together with the steam, passes upward. At the upper part of the chamber 9^a there is connected a pipe 38^a by which the 5 steam is discharged. A by-pass pipe 39^a connects the upper part of the chamber 9^a with the upper part of the reservoir 34^a.

It will be observed that in this construction, as in the one first described, the cold 10 water is first brought into contact with that part of the heating surface which surrounds the partly cooled gases, and then the water passes to the part of the heating surface which surrounds the burning gases and 15 finally the water, with the steam, engages that part of the heating surface which surrounds the gases of combustion. By the arrangement shown in Fig. 4, I have avoided the necessity for three separate water chambers 20 but have nevertheless retained the principal advantages present in the first described construction. The manner of operation of this embodiment of the invention and the advantages thereof are similar to those 25 already described, and repetition will be unnecessary.

It will be understood that many changes may be made in the construction illustrated and various substitutes of equivalents with- 30 out departing from the spirit of the invention.

What is claimed is:—

1. In a steam generator, the combination 35 of a heating chamber, a water container having a section divided from the remainder thereof and positioned adjacent the final or discharge part of the chamber, means for leading water into the said section, means for leading water from the said section first 40 to a part of the container adjacent the initial or combustion part of the chamber and then to a part of the container adjacent the intermediate part of the chamber, the said means including a reservoir separate from 45 the container and interposed between the said section and the said part adjacent the intermediate part of the chamber, and a by-pass pipe connecting the reservoir with the last said part of the container and positioned above the water level.

2. In a steam generator, the combination 55 of a heating chamber, a water container having three separate sections of which one is adjacent the final or discharge part of the chamber, the second adjacent the initial or combustion part of the chamber and the third adjacent the intermediate part of the chamber, a reservoir separate from the container, means for leading water successively 60 through the first section, the second section, the reservoir and the third section, and a by-pass pipe connecting the reservoir with the third section and positioned with its end above the water level in the reservoir.

65 3. In a steam generator, the combination

of a tubular heating chamber, a tubular water container surrounding the chamber and divided into a plurality of sections, a spiral vane in each section providing a spiral passage for the water, means for leading 70 water into the section of the container near the final or discharge part of the chamber, and means for leading the water from the said section first to a part of the container adjacent the initial or combustion part of 75 the chamber and then to a part of the container adjacent the intermediate part of the chamber.

4. In a steam generator, the combination 80 of a tubular heating chamber, a tubular water container surrounding the chamber and divided into a plurality of sections, a spiral vane in each section providing a spiral path for the water, means for leading water into the remote end of the section of the 85 container near the final or discharge part of the chamber, and means for leading the water from the near end of the said section to the opposite end of the container adjacent the initial or combustion part of the 90 chamber.

5. In a steam generator, the combination 95 of a vertical tubular heating chamber, a vertical tubular water container surrounding the chamber and divided into a plurality of sections, means for leading water into the remote end of the section of the container near the final or discharge part of the chamber, and means for leading the water from 100 the near end of the said section to the opposite end of the container adjacent the initial or combustion part of the chamber.

6. In a steam generator, the combination 105 of a vertical heating chamber in which combustion occurs in the upper part the gases of combustion being discharged downward; a vertical tubular water container surrounding the chamber and divided into three sections, means for leading water into the lower end of the lower section near the 110 final or discharge part of the chamber, means for leading the water from the upper end of the lower section to the upper end of the upper section adjacent the initial or combustion part of the chamber, 115 means for leading the water from the lower end of the last said section to the lower end of the third or intermediate section, and means for receiving steam from the upper part of the intermediate section.

7. In a steam generator, the combination 120 of a vertical heating chamber in which combustion occurs in the upper part the gases of combustion being discharged downward, a vertical tubular water container surrounding the chamber and divided into three sections, a spiral vane in each section providing a spiral path for the water, means for leading water into the lower end of the 125 lower section near the final or discharge 130

part of the chamber, means for leading the water from the upper end of the lower section to the upper end of the upper section adjacent the initial or combustion part of the chamber, means for leading the water from the lower end of the last said section to the lower end of the third or intermediate section, and means for receiving steam from the upper part of the intermediate 10 section.

8. In a steam generator, the combination of a vertical heating chamber in which combustion occurs in the upper part the gases of combustion being discharged downward, 15 a vertical tubular water container surrounding the chamber and divided into three sections, means for leading water into the lower end of the lower section near the final or discharge part of the chamber, means for 20 leading the water from the upper end of the lower section to the upper end of the upper section adjacent the initial or combustion part of the chamber, means for leading the water from the lower end of the last said 25 section to the lower end of the third or intermediate section, means for receiving steam from the upper part of the intermediate section, and spiral vanes located respectively in the several sections and providing a spiral path for the water through 30 each of them, the second vane having a greater pitch than the first and the third having a greater pitch than the second.

9. In a steam generator, the combination of a vertical heating chamber in which combustion occurs in the upper part the gases of combustion being discharged downward, a vertical tubular water container surrounding the chamber and divided into 35 three sections, means for leading water into the lower end of the lower section near the final or discharge part of the chamber, means for leading the water from the upper end of the lower section to the upper end of the upper section adjacent the initial or combustion part of the chamber, means for leading the water from the lower end of the last said section to the lower end of the third or intermediate section, means for 40 receiving steam from the upper part of the intermediate section, spiral vanes located respectively in the several sections and providing a spiral path for the water through each of them, and connectors between adjacent coils of the vanes serving to hold the coils properly spaced and also serving to deflect the water.

10. In a steam generator, the combination of a vertical heating chamber in which combustion occurs in the upper part the gases of combustion being discharged downward, a vertical tubular water container surrounding the chamber and divided into three sections, means for leading water into the lower 60 end of the lower section near the final or

discharge part of the chamber, means for leading the water from the upper end of the lower section to the upper end of the upper section adjacent the initial or combustion part of the chamber, a reservoir connected 70 to receive water and steam from the lower end of the last said section, means for leading water from the bottom of the reservoir to the lower end of the third or intermediate section, and means for receiving steam from 75 the upper part of the intermediate section.

11. In a steam generator, the combination of a vertical heating chamber in which combustion occurs in the upper part the gases of combustion being discharged downward, a vertical tubular water container surrounding the chamber and divided into three sections, means for leading water into the lower end of the lower section near the final or discharge part of the chamber, means for leading the water from the upper end of the lower section to the upper end of the upper section adjacent the initial or combustion part of the chamber, a reservoir positioned at the same elevation as the third or intermediate section and connected to receive water from the lower end of the upper section, means for leading the water from the bottom of the reservoir to the lower end of the intermediate section, means for receiving steam from the upper part of the intermediate section, and a gage glass connected with the reservoir and serving to indicate the level of the water in the reservoir and in the intermediate section.

12. In a steam generator, the combination of a vertical heating chamber in which combustion occurs in the upper part the gases of combustion being discharged downward, a vertical tubular water container surrounding the chamber and divided into three sections, means for leading water into the lower end of the lower section near the final or discharge part of the chamber, means for leading the water from the upper end of the lower section to the upper end of the upper section adjacent the initial or combustion part of the chamber, a reservoir connected to receive water and steam from the lower end of the upper section, means for leading the water from the bottom of the reservoir to the lower end of the intermediate section, means for leading the steam from the upper part of the reservoir to the upper end of the intermediate section, and means for receiving steam from the upper part of the intermediate section.

13. In a steam generator, the combination of a vertical heating chamber in which combustion occurs in the upper part the gases of combustion being discharged downward, a vertical tubular water container surrounding the chamber and divided into three sec- 125

- tions, means for leading water into the lower end of the lower section near the final or discharge part of the chamber, means for leading the water from the upper end of the 5 lower section to the upper end of the upper section adjacent the initial or combustion part of the chamber, a reservoir connected to receive water and steam from the lower end of the upper section, means for leading 10 the water from the bottom of the reservoir to the lower end of the intermediate section, means for leading the steam from the upper part of the reservoir to the upper end of the intermediate section, means for receiving 15 steam from the upper part of the intermediate section, and a gage glass connected with the reservoir and serving to indicate the level of the water in the reservoir and in the intermediate chamber.
- 20 14. In a steam generator, the combination of a vertical heating chamber in which combustion occurs in the upper part the gases of combustion being discharged downward, a vertical tubular water container surrounding 25 the chamber and divided into three sections, means for leading water into the lower end of the lower section near the final or discharge part of the chamber, means for leading the water from the upper end of the 30 lower section to the upper end of the upper section adjacent the initial or combustion part of the chamber, a reservoir, a pipe connected to deliver water and steam from the lower end of the upper section to the reservoir, the said pipe entering the reservoir and having an upturned part terminating near the top of the reservoir, means for leading the water from the bottom of the reservoir to the lower end of the intermediate section, 35 40 a by-pass pipe for leading the steam from the upper part of the reservoir to the upper end of the intermediate section, means for receiving steam from the upper part of the intermediate section, and a baffle in the 45 reservoir interposed between the outlet end of the water pipe and the inlet end of the steam by-pass pipe.
15. In a steam generator, the combination 50 of a heating chamber consisting of a single metal tube in which combustion occurs near one end the gases of combustion being discharged at the other end, a tubular water container surrounding the chamber and comprising three separate metal tubes, means for closing the ends of the tubes to form three 55 separate sections, means for leading water into the remote end of the tube near the final or discharge part of the heating chamber, means for leading the water from the near 60 end of the said tube to the remote end of the tube adjacent the initial or combustion part of the chamber, and means for leading the water from the near end of the last said tube

to the opposite end of the third or intermediate tube.

65

16. In a steam generator, the combination of a heating chamber consisting of a single metal tube in which combustion occurs near one end the gases of combustion being discharged at the other end, a tubular water container surrounding the chamber and comprising three separate metal tubes, a division plate between each two adjacent tubes, each plate closely engaging the heating chamber tube, means for closing the outer 70 ends of the end tubes, and means for leading water through the said water tubes successively.

75

17. In a steam generator, the combination of a heating chamber consisting of a single metal tube in which combustion occurs near one end the gases of combustion being discharged at the other end, a tubular water container surrounding the chamber and comprising three separate metal tubes, a division plate between each two adjacent tubes, each plate closely engaging the heating chamber tube, means for closing the outer 80 ends of the end tubes comprising stuffing boxes engaging the heating chamber tube, 85 and means for leading water through the said water tubes successively.

90

18. In a steam generator, the combination of a heating chamber consisting of a single metal tube in which combustion occurs near one end the gases of combustion being discharged at the other end, a tubular water container surrounding the chamber and comprising three separate metal tubes, the outer 95 ends of the end tubes being contracted to engage the heating chamber tube, a division plate between each two adjacent tubes, each plate closely engaging the heating chamber tube, stuffing boxes at the outer ends of the end tubes engaging the heating chamber tube, and means for leading water through the said water tubes successively.

100

19. In a steam generator, the combination of a heating chamber consisting of a single metal tube in which combustion occurs near one end the gases of combustion being discharged at the other end, a tubular water container surrounding the chamber and comprising three separate metal tubes, the last 110 said tubes being detachable from each other and from the heating chamber tube, a division plate between each two adjacent tubes, each plate closely engaging the heating chamber tube, means for closing the outer 115 ends of the end tubes, and means for leading water through the said water tubes successively.

120

In testimony whereof, I affix my signature.

JAS. P. FISHER.
